FIRE HYDRANT

John J. Smith, Decatur, Ill., assignor to Mueller Co.,
Decatur, Ill., a corporation of Illinois

Filed Dec. 21, 1965, Ser. No. 267

Term of patent 14 years

(Cl. D91—3)

FIGURE 1 is a side elevation view of one side of a fire hydrant embodying my new design;

FIGURE 2 is an end elevation view of one end of the fire hydrant shown in FIGURE 1;

FIGURE 3 is a side elevation view of the opposite side of a fire hydrant shown in FIGURE 1; and

FIGURE 4 is a top plan view of the fire hydrant embodying my new design.

The dominant features of my design reside in the portions shown in full lines.

I claim:

The ornamental design for a fire hydrant, as shown and described.
